UNITED STATES PATENT OFFICE.

DON CARLOS TRAVIS, OF KENOSHA, WISCONSIN, ASSIGNOR TO SIMMONS COMPANY, OF KENOSHA, WISCONSIN, A CORPORATION OF DELAWARE.

FOLDING COUCH.

Application filed September 12, 1924. Serial No. 737,222.

My invention relates to improvements in folding couches. Although certain features of the invention may be employed with other types of couches, the invention as a whole, 5 is of particular service in connection with that type of folding couch in which the bedding is stored between the relatively foldable portions of the structure when the couch is in folded condition.

10 The principal objects of my invention are to provide a couch of the character described which will be comfortable for sitting or lounging purposes, when not in use as a bed; to provide a construction of the character referred to in which ample space is provided 15 for the convenient storage of the necessary bedding; to provide a construction which may be manipulated without the expenditure of undue effort; to provide an arrangement in which the various folding parts of the structure automatically assume 20 their proper position when the couch is folded and unfolded; to provide a construction having improved pillow stops which are concealed 25 when the structure is in use as a couch; to provide a structure which shall be neat in appearance, light in weight, compact, simple, rugged, efficient, durable, and economical to manufacture, and in general 30 to provide an improved construction of the character referred to.

In the drawings which illustrate a selected embodiment of my invention, Fig. 1 is an end elevation of the couch showing same extended or unfolded for use as a bed of double width.

Fig. 2 is a partial plan view of the structure as shown in Fig. 1.

Fig. 3 is a view similar to Fig. 1, but 40 showing the couch folded.

Fig. 4 is a front or side elevation of the couch as shown in Fig. 3.

Fig. 5 is a section taken on the line 5—5 of Fig. 3.

45 Fig. 6 is a front view showing the head or back-rest in effective position.

Fig. 7 is a fragmentary end view similar to Fig. 1 showing the couch as used with ornamental foot and head boards, and

50 Fig. 8 is a fragmentary side elevation of the couch shown in Fig. 7.

The structure in its main elements comprises a stationary supporting frame of

couch width and a pair of relatively folding bed bottom sections, also of couch width and adapted to be relatively unfolded to form a bed bottom of substantially double the width of the couch. One of the sections is permanently located in face up position above the supporting structure while the other or folding section is adapted to swing upwardly and outwardly through an angle of 180 degrees from its position superposed face downward above the first mentioned section and into a position alongside said first section and away from the supporting structure. A space between the two sections when the couch is in normal or folded condition, serves to contain the bedding, including the pad or mattress which is permanently secured to the faces of the sections. A cushion is also secured to the opposite side of the folding section to form a comfortable surface for sitting or reclining upon.

The main supporting structure comprises 75 a set of four legs, the front or outer legs being designated as 10, and the rear or inner legs being designated as 11. Said legs are connected at their ends by cross members 12, while the front legs 10, are connected 80 together by longitudinal bars 13, and the rear legs 11 are connected by means of transverse bars 14. The ends are braced by oblique bars as at 15. The rear legs 11 are braced by members as at 17, riveted respectively to the legs 11 and the longitudinal bar 14, and the front of the structure is braced by means of a lower tie bar 18 with diagonal braces 19.

The upper ends of the front legs 10 are 90 extended upwardly as at 20, and in the upper ends of the extension 20, there are located pivot pins or studs 21. Said pivot pins 21 are preferably riveted into the parts 20, and extend inwardly to form journals 95 upon which pivot certain movable parts of the construction. Among said parts are levers 22, which in the present instance comprise short lengths of angle iron, the ends of which constitute arms, 23 and 24, extending in opposite directions from the pivot pin 21. To the ends of said arms by means of pins or rivets 25 and 26, there are pivoted the adjacent spaced side portions 100 of the floating section 27, and the folding section 28, said pins 25 and 26 passing re-

spectively through the end bars 29 and 30 of the sections. When the couch is extended to form a bed, as indicated in Fig. 1, the members 30, 24 and 29 at each end of the structure, which are made of angle iron, constitute in effect a substantially continuous rail, and lie in substantially the same plane. As shown best in Fig. 2, the horizontally projecting flanges of said angle iron members are apertured as at 32 to receive the hooked ends 33 of the helicals 34, to which the wire link bed fabric 35 is connected.

In order to resist the pull of said helicals 34, which are normally under considerable tension, there is employed a substantial diagonal brace bar 36 at each end of the structure, the lower end of said brace bar being riveted to the longitudinal bar 13, while the upper end of said braced bar is bent to extend coaxially with the pivots 21 and bears against the vertical flange 37 of the angle iron spacing lever. Preferably the upper end of said braced bar 36 is drilled out to fit around the inner end of the pivot pin 21, as indicated at 38 in Fig. 4. The rear ends of the end bars 30 of the floating section are held apart by a longitudinally extending bar 39, as shown in Fig. 1, which may be of angle iron construction. The front end of the end bars 29 of the folding section 28 are held apart by a bar 40. Said bar 40 for purposes of rigidity and to prevent relative twisting of the ends of the folding section, is preferably made in the form of a tube, such tube being of oval or circular cross section to avoid the presence of sharp edges.

As will be readily understood, the adjacent hinged sides of the floating section 30, and the folding section 29, are hingedly supported by the pivoted levers 22. I have designated the section 27 as "floating", because said section, although in its two positions occupying a position parallel with the floor, rises into position level with the height of the folding section 29, when the bar is unfolded and descends into the lower position shown in Fig. 2, when the structure is in use as a couch. The front side of said floating section 27 is controlled in its movement by the arm 24 of the space lever as previously described, while the rear side is supported and controlled in its movement by a pair of stationary cams located at the respective ends of the structure. As shown in the drawings, each of said cams comprises a stamped steel plate 41, having a bottom flange 42 riveted to the end bar 12, the main portion of the cam plate 41 extending upwardly and having a slightly offset upper extension 42 through which there is punched an oblique or diagonal slot 43. Said slot is preferably straight and serves as a

guide for a cam pin or stud 44, fixed in the inner or rear end of the cross bar 30 of the floating section. The offsets 42 are spaced apart the proper distance to permit free movement of the rear portion of the floating section 27 therebetween.

It has been found that in a couch of this general type of construction, unless special means be employed, a very considerable effort is required to unfold the structure, as it is usually necessary to stand at the side of the couch and bend over to pull up upon the bar 40 or corresponding part. This places the operator in a somewhat awkward position for applying any considerable force and some assistance is very desirable. In the present instance such assistance is provided by a pair of coiled tension springs 45, one at each end of the structure and connected respectively between the plate 41 and a lug 46 secured to the cross member 30 of the floating section and extending downwardly a short distance therefrom. Said spring 45 at all times, and particularly when the couch is in folded condition as shown in Fig. 3, exerts a strong force tending to pull the floating section 27 rearwardly or upwardly. Also such pull, when the couch is in its folded condition as shown in Fig. 3 is in such direction as to cause said pull to be exerted in a slightly upward direction, due to the fact that the front end of said spring 45 is located some distance below a line extending through the rear end of the spring, and the front end of the floating section. Such lifting tendency serves to reduce whatever slight friction which may be present between the cam pin and the slot 43, during the commencement of the unfolding movement.

The springs 45 which thus tend to draw the floating section inwardly obviously, when the couch is in the position as shown in Fig. 3, tend to rotate the space levers in a clockwise direction. In order to maintain said space levers in correct vertical position when the couch is folded, and also, which is just as important, in order to render the force of said spring 45 effective to assist in the initial unfolding movement, the outer ends of the arms 23 are made with shoulders or square corners as indicated at 47, positioned to abut or engage against the horizontal flanges of the end bars 29 of the folding section 28. The dimensions of said last named parts are such that the section 28 is maintained perpendicular to the spaced levers 23, and moves as a unit therewith during the initial unfolding movement of the couch with the assistance of springs 45, and until the said folding section approaches a vertical position, after which no considerable effort is needed to complete the unfolding.

It will be observed by reference to Fig. 1

that the lower horizontally extending flanges of the end bars 29 and 30 extend a short distance beyond the pivots 25 and 26 respectively, so that when the bed is extended as shown in said Fig. 1, the extremities of said flanges contact with the under surface of the horizontal flanges 48 of the space lever, so that neither of the pivots can rise above a horizontal plane passing through the pivot 21 and therefore the horizontal alignment of the sections and the space lever 24 will be fixedly maintained. In this connection it will be readily understood that the arm 24 of the space lever is relatively short and even if an excessive weight were placed upon the section 27, the lesser weight of the section 28, because of its much greater leverage, is ample to prevent the said section 28 from rising.

It will be manifest that in no case can the section 27 rise either because of excessive weight placed upon the section 28, or due to the spring 45, since the cam pin 44 is limited in its upward movement by the end of slot 43.

In connection with my improved couch, I employ a folding leg construction which has the desirable feature that the leg will fold up automatically during the initial half of the folding operation, and vice versa, the leg will not commence to unfold until the folding section passes the vertical position. To this end, each of the outer legs 49 is pivoted on a pin or rivet 50 adjacent the outer end of the folding section 28. The upper end of the leg 49 is extended above the section 28, as at 51, and in the extremity thereof, there is located a pivot pin 52. Said pivot pin 52 serves as a lower pivotal support for the bow shaped pillow stop 53, said pillow stop also being braced by a tie-bar 54, the inner end of which is secured to the pillow stop by a rivet 55, while the outer end of said tie-bar 54 is secured to the outer end of the pillow stop by means of a pivot pin 52.

The inner end of the pillow stop 53 is made with a depending L shaped bend 56, and is pivotally mounted on the stationary pivot pin 21. The distance between pivots 21 and 25 is substantially equal to the distance between pivots 50 and 52 so that when the folding section 28 is swung upwardly to a vertical position, the leg 49 will assume a position substantially parallel with the section 28, as will be seen from an inspection of Fig. 3. When the folding movement of the folding section 28 is further continued, there is no further change in relative positions of the leg, the pillow stop, and the section, for the reason that the space lever 24 and the section 28 then move as a unit around the stationary pivot 21.

The floating section 30 is equipped with a pillow stop 57, similar in appearance to the

pillow stop 53 on the folding section 28. Said pillow stop 57 is also for purposes of appearance, fitted with a tie bar 58, and is supported at its outer end by a rivet 59, and on the other end is secured in position on the section 27 by a pivot pin 44. It will be observed by reference to Figs. 2 and 3 that the pillow stops 53 and 57 are relatively offset so that they will nest without interference.

It will be understood that the pad or mattress is strapped or tied to the sections 27 and 28. Preferably such pad is of one piece or continuous, so that it overlies that portion of the bed fabric which is connected to the space levers. It will be understood of course, that when the couch is folded as shown in Fig. 3, the space levers locate the faces of the bed bottom sections a sufficient distance apart to admit the two thicknesses of pad therebetween, together with other necessary bedding such as pillows and blankets. In order to provide a comfortable seat, the obverse face of the folding section 28 is fitted with a pad secured thereto by straps or other means. It will be observed that with the construction shown, because of the fact that the longitudinal bar 13 is located a substantial distance below the pivot 21, the resiliency of the central portion of the extended bed fabric is not affected. Furthermore, when the couch is folded as shown in Fig. 3, the front edge of the couch has no undesirable hardness or rigidity as it is composed only of the strands of the flexible bed fabric. Also because of the fact that the space between the two sections is occupied by the pad and other bedding when the couch is sat upon, the weight of a sitting person is supported by both plies of the fabric.

An additional feature of my improved construction is the head or shoulder rest as shown best in Figs. 2 and 6. Said rest comprises a one piece U bar, the sides 60 of which are connected by a cross piece 61, the space between said cross piece and the end 62 of the U bar being crossed by a series of three fillers 63. The extremities of the said side pieces 60 are hingedly supported on thin steel slats 64 stretched between the cross bars 29, by means of end helicals 65. The elevated end of the head rest is maintained in raised position by means of a U-shaped strut 66, the strut 66 having side limbs 67, the extremities of which are bent around to enter apertures in small hinge plates 68, secured to the outer filler bars 63. Such pivotal connection permits the strut 66 to be swung parallel with the head rest and between the latter and the surface of the folding section 28, when the head rest is not needed. Small J-shaped clips 69, riveted to the end bar 29 serve as abutments for the lower end of the strut 66 when the head rest is in elevated position as shown in Fig. 6.

For the purpose of preventing the head rest from falling down when the bed is unfolded, I prefer to employ a small swinging button or catch 70, which is pivoted on the end bar 29, and may be swung around thru an angle of about 90 degrees to retain or release the head rest as occasion requires.

As is customary with couches of this general character, ornamental head and foot frames may be applied, in which case the pillow stop for the floating section may be dispensed with. Such ornamental foot and head frames, one of which is indicated in Figs. 7 and 8, are preferably made detachable. In such case, the detachable fastening may consist of a headed pin or rivet 71 secured in each of the legs of the main structure, and co-operating with a slot in an angle plate 72, secured to each of the posts 73 of the detachable ends.

The described details of construction being illustrated of merely one application of my invention, the scope of same should be determined by reference to the appended claim, said claim being construed as broadly

as possible, consistent with the state of the art.

I claim as my invention:

In a folding couch, the combination of a supporting frame, a floating bed bottom section, a depending arm pivotally connected at its lower end to one side of the floating section and pivotally connected at its upper end to the adjacent side of said supporting frame, a cam plate mounted on the opposite side of said frame and having an inclined cam surface for supporting the adjacent side of said floating section, a tension spring connected at one end to said cam plate below the lower end of said inclined cam surface and at its other end to said floating section at a point intermediate the cam and the arm, said spring normally tending to cause one side of said floating bed bottom section to move upwardly on said inclined surface and the other side to swing in an upward direction about said pivotal connection of said arm and under the control thereof.

DON CARLOS TRAVIS.
